United States Patent

Des. 235,442
Patented June 17, 1975

235,442

FISH LURE

Earl E. Miller, Knoxville, Tenn., assignor to
Brunswick Corporation, Skokie, Ill.

Filed Sept. 17, 1973, Ser. No. 397,958

Term of patent 14 years

Int. Cl. D22—05

U.S. Cl. D22—27

Fig. 1

Fig. 2

Fig. 3

FIG. 1 is a perspective view of the fish lure showing my new design;

FIG. 2 is a bottom view of my fish lure;

FIG. 3 is a front view of my fish lure;

FIG. 4 is a side view of my fish lure;

FIG. 5 is a top view of my fish lure;

FIG. 6 is a rear view of my fish lure;

FIG. 7 is a cut-away view of the tail portion showing the relationship between the spinner and the hook.

I claim:

The ornamental design for a fish lure, substantially as shown and described.
